(57) **CLAIM**

The ornamental design for a glove with slits for fingernails as shown and described.

DESCRIPTION

FIG. 1 is a front perspective view of a glove with slits for fingernails showing my new design;

FIG. 2 is a front perspective view of the glove with slits for fingernails thereof;

FIG. 3 is a front elevation view of the glove with slits for fingernails thereof;

FIG. 4 is a rear elevation view of the glove with slits for fingernails thereof;

FIG. 5 is a bottom plan view of the glove with slits for fingernails thereof;

FIG. 6 is a left elevation view of the glove with slits for fingernails thereof;

FIG. 7 is a right elevation view of the glove with slits for fingernails thereof; and,

FIG. 8 is a top plan view of the glove with slits for fingernails thereof.

Although shown in the context of a left hand glove with slits for fingernails, a glove with slits for fingernails of the present invention may also be incorporated in a right hand glove.

The broken lines on the knuckles of the thumb, index finger, and middle finger depict stitching and form a part of the claimed design. The broken lines on the tip of the palm side of the thumb and on the tip of the palm side of each finger depict stitching and form a part of the claimed design. The long-dash broken lines in FIG. 1 depict fingernails and form no part of the claimed design. All other broken lines in FIGS. 1-8 depict portions of the glove and form no part of the claimed design.

1 Claim, 8 Drawing Sheets
